UNITED STATES PATENT OFFICE

ERNEST S. LYDEN, OF DULUTH, MINNESOTA

ARM SHIELD

Application filed August 14, 1930. Serial No. 475,191.

This invention relates to arm shields to be used by an operator in the washing of automobiles, windows, or the like, and is designed particularly as a means for the prevention of water running down onto the arm or clothes of the operator.

The principal object is to produce a more efficient and practical device of this character than heretofore known.

10 Other objects and advantages of the invention will appear in the further description thereof.

Referring now to the accompanying drawings, forming part of this application, 15 and wherein like reference characters indicate like parts:

Figure 1 is a central transverse sectional view through one of the improved shields; and

20 Figure 2 is a plan view of an entire shield as it appears from the convex face thereof.

The device is preferably formed of a dished-like piece of rubber 1, circular in form, and of substantially uniform thickness throughout except as respects the margin of the axial hole 2 therethrough, and which marginal portion of the hole is formed with an enlarged annular bead 3 extending preferably upwardly within the 25 concaved side of the disc.

This hole 2 as is obvious is for the convenient slipping of the shield over the operator's arm as is common in such devices, and the inner circumferential face of the bead 3 is provided with the annular groove 4 for the purpose of not only increasing the resiliency of the bead, but to increase its adherence to the arm by suction like effect.

From the bead 3 there extends radially a 40 plurality of tapered reinforcing ribs 5 to reinforce and strengthen the disc, and adjacent the circumferential edge upon the opposite face is formed an extending annular flange-like drip bead 6, so that any 45 water being discharged from the concaved surface of the shield may not readily follow inwardly upon the opposite surface when moved about during its use.

From the foregoing it is apparent that I 50 have devised a simple, light and efficient

shield of the class described, and what I claim as new and desire to secure by Letters Patent, is:

Dished disc-like shield of the character described made of a single piece of flexible material having an axial hole therethrough, 55 an annular enlargement about the hole, a groove within the inner face of the enlargement, reinforcing ribs extending radially from the flange upon the inner face of the 60 shield, and an annular drip flange adjacent its marginal edge, and projecting from the convex surface thereof.

In testimony whereof I affix my signature.
